UNITED STATES PATENT OFFICE.

ROBERT WARFF, OF SAN FRANCISCO, CALIFORNIA.

COMBINATION WRENCH.

Application filed February 20, 1924. Serial No. 693,971.

To all whom it may concern:

Be it known that I, ROBERT WARFF, a citizen of the United States, residing at San Francisco, in the county of San Francisco 5 and State of California, have invented certain new and useful Improvements in Combination Wrenches, of which the following is a specification.

This invention pertains to wrenches for 10 the use of mechanics, and the object is to provide a combination wrench of novel design and which may be adapted for use in several ways and for several different purposes.

15 In the drawing—

Figure 1 is a side elevation of the wrench, the socket bar being omitted;

Fig. 2 is an edge view, the socket bar being omitted;

20 Fig. 3 is a side elevation showing the socket bar assembled in place;

Fig. 4 is an edge view showing the socket bar in place; and

Fig. 5 is a detail of the sliding jaw.

25 In carrying out this invention, I provide a flat wrench shank 1, which is made thick enough to afford the requisite rigidity and yet thin enough and with straight and parallel edges 2 to serve as ruling edges. 30 One or both of these edges may be marked off into inches and fractions thereof, as shown at one of the edges in the drawing.

One end of this shank is reduced to form 35 a screw-driver 3, and at the opposite end is rigidly mounted a permanent wrench jaw 4. The jaw 4 is preferably formed integrally with the shank 1 and slightly greater in thickness, and is set exactly perpendicular to the shank 1, so that this jaw and 40 shank may be employed as a small square, if desired. The end of the jaw 4 adjacent the shank is extended slightly as shown at 45 5, to serve as a hammer. The opposite end of the jaw 4 is tapered off in the plane of the jaw and shank, as shown at 6. At the 50 juncture of the shank 1 with the jaw 4 is formed a squared nut-engaging aperture 7, which is set at an angle of 45 degrees relative to the edges of the shank 1 and jaw 4. 55 Another similar nut-engaging aperture 8 is formed medially through the shank 1.

A sliding jaw 9 is provided of the same thickness as the jaw 4 and having a shank

12 through which the flat aperture 10 is formed adapted to slidably engage the 55 shank 1, and with the free end of the jaw 9 tapered off as shown at 11 to meet the tapered end 6 of the jaw 4. Angular notches 13 are cut in each side of the shank 12 of the jaw 9, adapted to register with 60 the angular edges of the apertures 7 and 8 as the shank 12 is moved up to those apertures. A set-screw 14 is threadedly mounted through one side of the shank 12 and the inner end thereof bears upon the 65 face of the shank 1 as means for locking the shank 12 in any set position. A square socket bar 15 is provided, adapted to slide freely through the aperture 8 of the shank 1, and this socket bar has a threaded end 16 70 upon which may be screwed socket wrenches 17 of various standard sizes.

This implement has various uses. The bar 15 being removed, the jaw 9 may be locked 75 slightly spaced from the jaw 4, and the device used as a nail puller; the apertures 7 and 8 may be used for turning nuts; a measure, a rule, a square, a hammer, and a screw-driver are also afforded. By inserting the bar 15 through the aperture 8 and then locking the shank 12 tightly down upon the bar 15, as indicated in dotted lines in Fig. 3, an 80 excellent socket wrench is provided, the shank 1 then serving as a handle for turning the bar 15.

85 While I have herein described a certain specific manner and method of constructing and assembling the elements of my invention, it is understood that I may vary from the same in minor details, not departing 90 from the spirit of my invention, so as best to construct a practical device for the purpose intended, as defined in the appended claim.

I claim:

In a device of the kind described, a flat, 95 rule-like main shank having nut-engaging apertures formed therein; a sliding jaw and shank mounted upon the main shank, the shank of the sliding jaw having notches formed therein adapted to register with the 100 nut-engaging apertures of the main shank; and means for locking the sliding jaw in any set position upon the main shank.

In testimony whereof I affix my signature.

ROBERT WARFF.
